Primary Examiner — Rashida Johnson*Assistant Examiner* — Shannon Morgan(74) Attorney, Agent, or Firm — Novick, Kim & Lee, PLLC; Jae Youn Kim(57) CLAIM

I claim the ornamental design for a food storage container, as shown and described.

DESCRIPTION

FIG. 1 is a top, front perspective view of a food storage container showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a sectional view taken along line 8-8 of FIG. 6 showing my new design.
